(57) **CLAIM**

The ornamental design for an electrical connector, as shown and described.

DESCRIPTION

FIG. 1 is a perspective view of an embodiment of an electrical connector;

FIG. 2 is a front view of the embodiment of the electrical connector of FIG. 1;

FIG. 3 is a rear view of the embodiment of the electrical connector of FIG. 1;

FIG. 4 is a first side view of the embodiment of the electrical connector of FIG. 1;

FIG. 5 is a second side view of the embodiment of the electrical connector of FIG. 1;

FIG. 6 is a top view of the embodiment of the electrical connector of FIG. 1;

FIG. 7 is a bottom view of the embodiment of the electrical connector of FIG. 1;

FIG. 8 is a perspective view of another embodiment of an electrical connector;

FIG. 9 is a front view of the embodiment of the electrical connector of FIG. 8;

FIG. 10 is a rear view of the embodiment of the electrical connector of FIG. 8;

FIG. 11 is a first side view of the embodiment of the electrical connector of FIG. 8;

FIG. 12 is a second side view of the embodiment of the electrical connector of FIG. 8;

FIG. 13 is a top view of the embodiment of the electrical connector of FIG. 8; and,

FIG. 14 is a bottom view of the embodiment of the electrical connector of FIG. 8.

(Continued)

The broken lines show portions of the electrical connector that form no part of the claimed design.
